Patented May 10, 1921

UNITED STATES PATENT OFFICE.

ELMER N. CHILDS, OF YALE, IOWA.

ADJUSTABLE TONGUE ATTACHMENT FOR VEHICLE-HOUNDS.

1,377,314.

Specification of Letters Patent. Patented May 10, 1921.

Application filed February 11, 1920. Serial No. 357,866.

To all whom it may concern:

Be it known that I, ELMER N. CHILDS, a citizen of the United States, residing at Yale, in the county of Guthrie and State of Iowa, 5 have invented certain new and useful Improvements in an Adjustable Tongue Attachment for Vehicle-Hounds, of which the following is a specification.

This invention relates to new and useful 10 means for attaching tongues to wagon hounds, and has for its object, broadly, to provide a frame adapted to be adjusted both longitudinally and transversely to occupy 15 the area between the convergent wagon hounds when secured to the tongue, one of the specific objects being to provide an attachment consisting of few and simple parts so that manufacture will be economical and that durability may be attained, also which 20 may be conveniently adjusted and may be readily applied to wagon tongues regardless of their form in cross-section.

The invention is fully described herein and the novel features are particularly 25 pointed out in the appended claims, and illustrated in the accompanying drawing, wherein,—

Figure 1 is a plan view of an adjustable tongue attachment embodying my invention. 30 Fig. 2 is a side view of the same. Fig. 3 is a rear end view of the tongue attachment. Fig. 4 is a transverse section on line 4—4 of Fig. 1. Figs. 5 and 6, respectively are plan and end views of a bracket.

35 In the drawing, numeral 5 indicates a wagon tongue which may be constructed of any desired material and may have any desired form in cross-section. I provide a frame to be mounted upon the rear end of 40 the tongue between the wagon hounds 6, said frame, preferably, being constructed of attenuated, metallic plates, so that it may have a comparatively light weight but will sustain stresses ordinarily directed thereto, 45 and consisting, in part, of a pair of supporting plates respectively indicated at 7 and 8, these being disposed substantially parallel 50 between its ends with a slot 9 for receiving a bolt 10, so that it may be adjusted longitudinally of the tongue.

Numerals 11 indicate a pair of auxiliary hounds each being angular in cross-section 55 and provided with an aperture for receiving a tongue-rod 12, the tongue and wagon-hounds also being apertured for receiving

said rod, said rod permitting the usual vertical swinging movements of the tongue between the hounds 6.

Rigidly mounted upon the tongue, forwardly of the auxiliary hounds and in line with the plates 7 and 8, is an anchor-plate 14; and at 15 are indicated a pair of links, each having a pivotal connection for its inner end upon the plate 14, as indicated at 15', the outer end of each link having a pivotal connection, as indicated at 16, upon the horizontal flange *a* of an auxiliary hound 11.

Numerals 17 indicate brackets arranged in pairs, each pair being mounted upon the lower side of a supporting-plate 7 or 8, near an end thereof, each horizontal flange *b* of a bracket and each plate 7 and 8, near the respective ends of the latter, being traversed by a pair of bolts 18.

Numerals 19 indicate spacing-bolts, each being connected with an auxiliary hound by a bolt 20; and it will be understood, that 80 by rotating the nuts 21 and 22 upon bolts 19, at the opposite sides of the vertical flanges *c* of the brackets 17, the auxiliary hounds 11 may be adjusted to be disposed at required inclinations or angles to the 85 tongue 5, corresponding to the inclination of the wagon hounds 6.

Numerals 23 indicate alining-plates, each having its outer end interposed between the horizontal flange *a* of an auxiliary hound 90 and the head of a spacing-bolt 19 and traversed by a bolt 20, the inner ends of said alining-plates being disposed between the upright wings *d* of the horizontal flanges *b* of the brackets 17, intermediate a pair of 95 bolts 18, said plates 23 operating to maintain the horizontal flanges *a* of the auxiliary hounds in alinement with the rectilinear supporting-plates 7 and 8, the wings *d* in conjunction with the bolts 18 tending to 100 prevent any horizontal swinging movements of said plates 23.

It will be seen that the metallic frame may be adjusted to maintain the vertical flanges *c* of the auxiliary hounds closely 105 adjacent to the wagon hounds, and since the latter have inclinations which are not uniform on all vehicles, it is important that the frame shall sustain all stresses directed horizontally to the tongue, and that a construction for this purpose may have adjustments both longitudinally and transversely of the tongue.

In operation, after the tongue-rod has

been inserted in the apertures of the hounds and wagon tongue and apertures of the vertical flanges *e* of the auxiliary hounds 11, the plates 7 and 8 are adjusted longitudinally of the tongue, and adjustments are then made of the remaining parts as described and for the purposes mentioned. On account of the use of the bolts 19, accurate adjustments may be made for the auxiliary hounds to dispose them parallel with and closely adjacent to the wagon hounds 6, and since the mounting of the threaded ends of these bolts are below and somewhat remote from the rectilinear supporting-plates 7 and 8, said bolts operate to great advantage in sustaining stresses directed to the auxiliary hounds. It will be understood that by use of the pairs of bolts 18, the alining-plates 23 are pressed between the horizontal flanges of the brackets and supporting-plates 7 and 8, the upright wings *d* also engaging the under sides of the supporting-plates at the longitudinal edges of said plates 23, these parts aiding in resisting the stresses mentioned, and aiding in maintaining the alinement mentioned.

While I have described construction in detail, I do not wish to be understood as limiting myself to exactness in this respect, and changes in form, size, proportion and minor details may be made within the scope of the invention as determined by the appended claims.

I claim:

35. 1. In a tongue attachment for vehicle hounds, a pair of supporting-plates adapted to be disposed transversely of the tongue and to be adjusted longitudinally thereof, a plurality of brackets each having a horizontal flange connected with a supporting-plate and provided with an apertured, vertical flange, spacing-bolts each having a threaded part engaging in a vertical flange of a bracket and projecting outwardly of an end of a supporting-plate, a pair of auxiliary hounds outwardly of the sides of the tongue and connected with the spacing-bolts, and revoluble members on the threaded parts of the spacing-bolts for moving the latter and said auxiliary hounds transversely of the tongue.

2. In a tongue attachment for vehicle hounds, a pair of supporting-plates adapted to be disposed transversely of the tongue and to be adjusted longitudinally thereof, a plurality of brackets each having a horizontal flange with upright wings and connected with a supporting-plate and having an apertured, vertical flange, a plurality of spacing-bolts each having a threaded part engaging a vertical flange of a bracket and projecting outwardly of an end of a supporting-plate, a pair of auxiliary hounds connected with the spacing-bolts, a plural-

ity of alining-plates each being connected with an auxiliary hound and disposed between the upright wings of the horizontal flange of a bracket, and revoluble members on the threaded parts of the spacing-bolts for moving the latter and said auxiliary hounds transversely of the tongue.

3. In a tongue attachment for vehicle hounds, a pair of supporting-plates mounted upon and disposed transversely of the tongue, a pair of auxiliary hounds, brackets at opposed sides of the tongue each being mounted upon and having an apertured flange projecting downwardly from a supporting-plate, a plurality of spacing-bolts connected with the auxiliary hounds each engaging in an aperture of a flange of a bracket, and means engaging the flanges of the brackets for moving said bolts longitudinally of the supporting-plates to cause a movement of the auxiliary hounds.

4. In a tongue attachment for vehicle hounds, a pair of supporting-plates mounted upon and disposed transversely of the tongue, a pair of auxiliary hounds, brackets at opposite sides of the tongue each being mounted upon and having a flange disposed transversely of a supporting-plate, a plurality of spacing-bolts connected with the auxiliary hounds each engaging one of said transversely disposed flanges, means engaging the transversely disposed flanges for moving said bolts longitudinally of the supporting-plates to cause movements of the auxiliary hounds, and a plurality of alining-plates each being connected with an auxiliary hound and a supporting-plate.

5. In a tongue attachment for vehicle hounds, supporting-plates adapted to be disposed transversely of the tongue and to be adjusted longitudinally thereof, a pair of auxiliary hounds, brackets at opposite sides of the tongue each being mounted upon the lower side and having an apertured flange disposed transversely of a supporting-plate, spacing-bolts connected with the auxiliary hounds each engaging in an aperture of the flange of a bracket, means engaging the flanges of the brackets for moving said bolts longitudinally of the supporting-plates to cause a movement of the auxiliary hounds, a plurality of alining-plates each being connected with an auxiliary hound engaging a supporting-plate, each bracket being provided with a pair of upstanding wings for engagement with an alining-plate and a supporting-plate.

In testimony whereof I have affixed my signature in presence of two witnesses.

ELMER N. CHILDS.
